UNITED STATES PATENT OFFICE

2,532,439

SHEET-METAL GAS BURNER

Albert H. Berger, Rocky River, Ohio, assignor, by
mesne assignments, to The Consolidated Iron-
Steel Manufacturing Company, Cleveland,
Ohio, a corporation of Ohio

Application December 22, 1945, Serial No. 636,627

4 Claims. (Cl. 158—114)

1

The invention relates to burners for fuel gas combustion, and particularly to novel burners of this nature especially adapted for use in a domestic gas stove.

An object of the invention is to provide a burner structure producible from sheet metal in a form which can be readily and rapidly fabricated from available materials, and at low cost.

Other objects and advantages will be apparent from a study of the following specification in conjunction with the attached drawings, in which:

Fig. 1 is a top plan view of a burner constructed in accordance with the teachings of the present invention; Fig. 2 is a vertical sectional view taken on the line 2—2 of Fig. 1; Fig. 3 is a view, taken in section similarly to Fig. 2, but showing the cover and base members slightly separated preparatory to assembly thereof; Fig. 4 is an end view as seen from the position of the line 4—4 of Fig. 2; Fig. 5 is a sectional view, taken similarly to Fig. 2, but showing a slightly modified form of the invention; Fig. 6 is a top plan view, similar to Fig. 1 in some respects, but showing another slightly modified form of the invention; Fig. 7 is a vertical sectional view taken on the line 7—7 of Fig. 6; Fig. 8 is a perspective view of one of the baffle members shown in Figs. 6 and 7; Fig. 9 is a top plan view of a fragmentary portion of another burner embodying my invention; and Fig. 10 is a sectional view taken on the line 10—10 of Fig. 9.

Before the present invention here illustrated is described in detail, it is to be understood that the invention here involved is not limited to the details of construction or the specific arrangement of parts here illustrated or described, as the invention obviously may take various forms. It also is to be understood that the phraseology or terminology herein employed is for the purpose of description and not of limitation, the scope of the present invention being defined in the appended claims.

Referring first to the embodiment shown in Figs. 1 to 4 my novel burner 10 is assembled by uniting two sheet metal elements, conveniently shown as separated in Fig. 3, the elements being hereinafter identified as a base 11 and a cover 12. The cover is of banjo-like form, having a relatively flat top wall 13, and a peripheral depending wall 14 which is outturned at the bottom to provide an attaching flange 15. The base 11 is shaped similarly to the cover 10, when viewed in top plan, but is slightly larger in overall dimensions than the cover, the excess stock

2

thus provided being turned upwardly and inwardly at 17 (as indicated in dotted line in Fig. 3, and in full line in Fig. 2) to hold the cover and the base in fixed assembly.

5 The central chamber thus provided between the cover and the base has a large, generally circular portion 20, a smaller end portion 21, and a connecting neck portion 22. In the preferred embodiment here shown, the wall 13 of 10 the cover is provided with an aperture 24 centrally disposed with respect to chamber portion 20. Axially aligned with aperture 24 in the cover is an aperture 25 in the base 11. The circumferential edge of aperture 25 is forced upwardly, 15 by pressing, spinning, stamping, or otherwise, and is outturned to provide a flange 26, as shown in dotted line in Fig. 3 and in full line in Fig. 2. This flange is crimped around the edge of the aperture 24, thereby providing a central columnar support consisting of the tubular portion 27 which was upturned from the base. This structural feature greatly strengthens the burner assembly.

20 The wall of end chamber portion 21 is provided with an inlet port 30 for the reception of a gas discharge nipple 31. The top wall of end chamber portion 21 is provided with a slot 32 constituting an air intake port. A conventional mixing plate 33 is provided with a similar slot 34, the mixing plate being rotatably mounted 30 above said intake port. It will be understood by those familiar with burner construction that the mixing plate rotates on a pivot consisting of screw 35, the plate being adjustably fixed in any suitable position for admitting the desired amount of air to the burner chamber.

25 The top wall of chamber portion 20 is provided with a spaced series of radial ridges 37, perforated at 38 to permit discharge of the fuel mixture, said mixture being of course ignited immediately above ridges 37.

30 The structure shown in Fig. 5 is generally similar to that of the preceding figures, except that in Fig. 5 the mixing plate 33 is situated on the base 11 which forms the bottom wall of chamber 21.

35 Figs. 6 to 8 show a burner similar in many respects to that shown in the preceding views, but I have added a plurality of baffles 40 of semi-cylindrical form, each baffle having a base flange 41 for attachment by welding or otherwise to an inner wall of chamber portion 20. Preferably, as here shown, these baffles are spaced around the central columnar elements, and are 55 placed one between each adjacent pair of ridges

37. As shown they are securely fixed to the base 11. The baffles may be provided with perforations 43. The purpose of these baffles is to produce diversionary fluid currents in the gaseous mixture and the perforations 43 promote this end.

It will be apparent that all elements of the structure shown in the various views may be formed cheaply from sheet metal, with the exception only of the conventional screw 35. The structures are readily assembled and are surprisingly strong and sturdy. They are much lighter and cheaper than conventional stove burners which are often formed from cast iron by a casting and machining process involving a number of relatively expensive labor operations.

Figs. 9 and 10 illustrate yet another embodiment of my invention. By reason of rapid temperature changes and other causes, the burner surface in the neighborhood of ridges 37 is susceptible to corrosive attacks. I have discovered that if the concave lower or inner surface be filled with metal, preferably of the same or a similar alloy to that of the burner, these corrosive attacks are greatly reduced. In Figs. 9 and 10 an elongated slug of metal 45 is welded or otherwise attached within the inner concavity 46 of the ridge 37, and the ridge and slug are perforated at 47 to permit passage of the gas.

What I claim is:

1. A burner for fuel gas comprising a cover and a base both formed from sheet metal united to enclose therebetween a mixing chamber, said chamber having a larger portion, and a smaller end portion, and a neck portion connecting said larger and smaller portions, both said portions being generally circular in common horizontal planes, said cover and base having peripheral edges crimped one upon the other to hold said base and cover together, a wall portion of said end chamber being provided with an opening to permit intake of fuel gas therethrough to said chamber, another wall portion of said end chamber being provided with an air intake port, said port being variable in size by means of a mixing plate adjustably mounted thereupon, a top wall portion of said larger chamber portion being perforated to permit discharge of a combustible fuel mixture therethrough, a plurality of fin-like sheet metal baffle members disposed within said larger chamber portion and affixed to an inner wall thereof to produce diversionary fluid currents in the fuel-air mixture for more thorough mixture thereof.

2. A burner for fuel gas comprising a cover and a base both formed from sheet metal and united to enclose a mixing chamber, said chamber having a larger portion, and a smaller end portion and a neck portion connecting said larger and smaller portions, both said portions being generally circular in common horizontal planes, said cover and base having peripheral edges crimped one upon the other to hold said base and cover together, the central portion of the upper wall of said larger chamber portion having a circular aperture therein, the central portion of the lower wall of said larger chamber portion having an axially aligned aperture, the edge of said last named aperture being drawn upwardly and mutually crimped with the edge of said first named aperture to provide a centrally disposed tubular support, a side wall portion of said end chamber being provided with a fuel intake port, another wall portion of said end chamber being provided with an air intake port, an adjustable

air mixing plate mounted adjacent said air intake port for adjusting the area of said air intake port, the top wall portion of said chamber surrounding said tubular support being perforated to permit discharge of a combustible mixture therethrough, a plurality of generally arcuate fin-like sheet metal baffle members affixed to the inner bottom wall of said larger chamber portion, and spaced around said columnar support, and extending upwardly into the path of travel of the fuel-air mixture to produce diversionary fluid currents in the fuel-air mixture for more thorough mixture thereof.

3. A burner for fuel gas comprising a one piece cover and a one piece base both formed from sheet metal united to enclose therebetween a mixing chamber, said mixing chamber comprising a larger main portion, and a smaller end portion, both portions being generally circular in horizontal planes, and a neck portion connecting said main and end portions, said cover having a peripheral depending side wall and being generally of downwardly open cup form, said base being generally planar and spaced from the cup bottom of the cover, the peripheral edges of the base and side wall being crimped together to hold said base and cover together, the depending cup side wall of said end portion being provided with an opening to permit intake of fuel gas therethrough to said mixing chamber, the cup bottom at the end portion being provided with an air intake port, said port being variable in size by means of a mixing plate adjustably mounted thereupon, the cup bottom at the main portion being perforated to permit discharge of a combustible fuel mixture therethrough.

4. A burner for fuel gas comprising a one piece cover and a one piece base both formed from sheet metal united to enclose therebetween a mixing chamber, said mixing chamber comprising a larger main portion, and a smaller end portion, both portions being generally circular in horizontal planes, and a neck portion connecting said main and end portions, said cover having a peripheral depending side wall and being generally of downwardly open cup form, said base being generally planar and spaced from the cup bottom of the cover, the peripheral edges of the base and side wall being crimped together to hold said base and cover together, the depending cup side wall of said end portion being provided with an opening to permit intake of fuel gas therethrough to said mixing chamber, the base at a portion thereof under the said smaller end portion of the cover, being provided with an air intake port, said port being variable in size by means of a mixing plate adjustably mounted thereon, the cup bottom at the main portion being perforated to permit discharge of a combustible fuel mixture therethrough.
